(57) **CLAIM**

The ornamental design for a pressure washer trigger gun, as shown and described.

DESCRIPTION

FIG. 1 is a perspective view of our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a perspective view showing a pressure washer trigger gun in a position of use with environment.

The broken lines represent portions of the pressure washer trigger gun and environment that form no part of the claimed design.
